UNITED STATES PATENT OFFICE.

ARTHUR FUNK, OF NEW YORK, N. Y.

SKIRT MARKER.

Application filed August 17, 1920, Serial No. 404,154. Renewed February 10, 1923.

To all whom it may concern:

Be it known that I, ARTHUR FUNK, a citizen of the United States, and a resident of New York, in the county of New York 5 and State of New York, have invented certain new and useful Improvements in Skirt Markers, of which the following is a specification.

This invention relates to improvements in 10 skirt markers and has for its principal object to provide a device which will avoid the necessity of using pins, chalk, or other marking means for determining the proper length of a skirt.

15 Another object of the invention resides in the provision of a device which may be easily and cheaply constructed and readily adjusted to meet varying requirements.

With these and other objects in view the 20 invention consists of a novel construction, combination and arrangements of parts which will be fully set forth in the following specification, claimed and illustrated in the accompanying drawings, in which:—

25 Figure 1 is a side view in elevation showing the device in use and illustrating a portion in section to more clearly illustrate details of construction.

Figure 2 is a top plan view of the device.

30 Figure 3 is an enlarged sectional view of a portion of one of the uprights showing the ring-supporting hook in detail.

Figure 4 is a perspective view showing a modified form of structure.

35 Figures 5, 6 and 7 are detail views of parts used therein.

Referring to the drawings in detail, the numeral 5 designates a base, preferably circular in plan as illustrated in Fig. 2. Se- 40 cured at spaced intervals to the base around its periphery are uprights which are pro- vided with graduations 7 on the face. Each upright is provided at spaced intervals on its outer face with a plurality of keyhole 45 slots 8 in which the head 9 of a stud is re- movably secured. This stud is carried at the rear end of a sleeve 10 in which is slidably mounted a plunger 11 carrying a hook 12. This plunger is provided on one face with 50 suitable graduations 13, and is adapted to be adjusted into and out of the sleeve 10.

Obviously, the sleeves 10 with their hooks 12 are secured to the uprights as illustrated in the drawings and when in such position 55 will support the skirt clamping rings to be hereafter described.

The skirt clamping members above referred to constitute the inner and outer rings 14 and 15 respectively, which are cut away, as at 16 and 17, to form overlapping 60 tongues, so that the ring may be readily adjusted to various diameters. The outer tongue of the outer ring and the inner tongue of the inner ring are slotted as at 18, to receive adjusting screws 19 which are 65 provided with wing nuts 20 and it will be seen that by loosening the wing nuts the rings may be varied in diameter to fit skirts of varying diameters.

In use, the hooks 12 are adjusted to the 70 proper height and the inner ring 14 is ad- justed to fit the inner diameter of a skirt. The outer ring is then adjusted to fit the outer diameter of the skirt and when the two 75 rings are brought into the position illus- trated in the drawings, it will be obvious that the skirt will be clamped in place and the person expecting to wear the garment will stand on the platform or base 5 and the rings may be adjusted to the desired 80 point after which the skirt may be marked, cut off to the proper length and it will be obvious that it will hang properly through- out its entire circumference.

In the modified form of the invention, 85 illustrated in Figs. 4 to 7 inclusive a ring 21 is substituted in lieu of the base and has secured thereto at spaced intervals uprights 22 provided with spaced keyhole openings 23. These uprights each comprise a pair of 90 sections hinged together as at 24 and it will be obvious that the two sections may be folded back upon each other for storage pur- 95 poses. Suitable rollers or casters 25 may be secured to the bottom of the ring 21 to per- mit the device to be easily moved about.

A plurality of telescopically adjustable 100 brackets 26 is provided and the inner end of each is provided with a headed stud 27 for engagement in the key hole slots 23. It will thus be apparent that the brackets may be adjusted to various heights on the uprights and the weight of the brackets on the upper sections will serve to hold the same ex- tended. The outer section of each bracket is 105 provided with a lip 28 for supporting the skirt clamping rings 29 and 30. The ends of these rings overlap as shown and are arranged so that the rings may be adjusted to fit rings of varying diameters. The wing 110 nuts and bolts 31 cooperate in retaining the rings in proper adjustment. Graduations

32 may be arranged in the rings to indicate their diameters and similar graduations 33 are arranged on the telescoping sections of the brackets so that the brackets may be 5 adjusted to equal length.

The operation of the modified construction is essentially the same as that previously described except that the uprights may be folded back to enable the device to 10 be easily stored in a relatively small space.

While in the foregoing there has been shown and described a preferred embodiment of this invention, it is to be understood that certain minor changes in the details in 15 the construction, combination and arrangement of parts may be resorted to without departing from the spirit and scope of the inventions as claimed.

1. A skirt marker comprising a circular 20 base ring, uprights secured to the periphery

of the ring, said uprights having key-hole slots, telescopically extensible brackets, studs on the brackets for projection into the key-hole slots whereby the brackets are removably and adjustably secured to the uprights, an adjustable ring carried by the end 25 elements of said brackets and a second adjustable ring cooperating with the first ring in marking the bottom edge of a shirt.

2. A skirt marker comprising a base ring, 30 sectional uprights on the ring, supporting brackets adjustable on the uprights, adjustable clamping rings resting on the brackets, hinges connecting the sections of said uprights and castors secured to the base of said 35 brackets.

In testimony whereof I have signed my name to this specification.

ARTHUR FUNK.
